UNITED STATES PATENT OFFICE.

EDWARD DAVIES, OF LONDON, ENGLAND.

APPARATUS FOR TREATING SPENT HOPS.

SPECIFICATION forming part of Letters Patent No. 288,553, dated November 13, 1883.

Application filed May 29, 1883. (No model.) Patented in England October 24, 1882, No. 5,067.

To all whom it may concern.

Be it known that I, EDWARD DAVIES, a subject of the Queen of England, residing at London, England, have invented new and useful 5 Improvements in the Treatment of Spent Hops and in Apparatus therefor, (for which I have obtained a patent in Great Britain bearing date October 24, 1882, No. 5,067,) of which the following is a specification.

10 The object of this invention is the utilization of the waste material known as "spent hops," so that the said hops may be used again, and the bitters, &c., contained therein utilized, a great saving being thereby effected.

15 The said invention will be best understood by reference to the accompanying drawings, in which Figure 1 is a front elevation of the machine; Fig. 2, a back elevation. Fig. 2' is a back elevation, showing the fan for exhausting 20 the fumes from the drying or heating chamber; Fig. 3, a plan. Fig. 3^a is a vertical section of the hopper to more clearly show the operation; Fig. 4, a longitudinal section of the drying-cylinder, with a long Bunsen burner underneath; and Fig. 5, a longitudinal section of the separating-cylinder.

25 The apparatus will be best understood from the plan, Fig. 3.

30 A is the drying-cylinder on the line x y, Fig. 3; and B, the separating-cylinder. C is a hopper, across which are two slowly-revolving shafts, C' and C'', having arms or equivalent, C³, to separate the hops and keep them from forming into lumps or balls.

35 A grating is placed across the hopper just over the top shaft, and upon this the hops are placed. The arms C³, in revolving, come up through the spaces in the grating between the bars, and as said arms descend they draw in 40 with them some of the hops to the lower portion of the hopper, so that a regular feed is the result, instead of the hops falling in in a lump, as would be the case if this or a similar one were not employed. This is shown in 45 Figs. 1 and 3, where P is the grating.

45 A spout, D, leads from the side of the hopper, at the bottom, into the drying-cylinder A, and a sliding door or panel, D', arranged within the hopper, is held back by a spring or 50 equivalent, D'', leaving the passage open, while a central arm upon shaft C'' is so placed as to

catch this slide and move it against the spring as it passes. As soon as the door is free from the arm it flies back under the influence of the spring D'', and so shakes the hops forward and 55 downward into the cylinder A.

An adjustable door or slide, D³, in the side of the hopper is set open at the proper distance to supply the hops at the desired speed to the cylinder A. Upon the shaft A' of the 60 cylinder A are wings or beaters A², spirally arranged, so as to stir up and gradually push the hops along toward the far end of the cylinder A, whence they are conveyed in any convenient manner to the separating-cylinder B. 65

The cylinder A is heated in any required manner, a Bunsen burner, E, being shown in the drawings, and I find this to answer well.

An elevator, F, Figs. 2 and 3, which is located to the rear end of the machine, and 70 which communicates with both the drying and separating cylinders, carries the hops as they leave the rear end of cylinder A to the rear end of cylinder B, which they traverse in the opposite direction to that in A, and come out 75 at the front of the machine, near the hopper, where they first entered.

The shafts C' and C'' are driven from a pulley on shaft A' by a cord or equivalent, C⁴, and it may be added that all the shafts revolve slowly. The apparatus is driven by a pulley or handle upon whichever of the main shafts is most convenient, and the various shafts are driven from one another by pulleys and belts, as shown in the drawings, or by 85 gearing; but belts are most convenient.

A rod, G, upon a pin G', fixed in the end of the cylinder A, has its other end connected by a pin, G², with a disk, g, upon the shaft G³, so that as G³ revolves an oscillating motion is 90 imparted to the cylinder A, which helps to dislodge and break up the hops within. The end of the cylinder is closed in any convenient manner, so as to keep in the heat and smell, and a ventilating-tube, H, leads from cylinder A to 95 the open air, or to a chimney, so as to conduct away the fumes given off during the drying process, and, where desired, an exhaust-fan, I, may be connected with this, so as to draw off the fumes more rapidly. Cylinder B has also 100 its shaft B' with arms or beaters B² set in the opposite direction to those of cylinder A, so

that the hops are carried back again to the same end of the machine that they started from.

The frame-work may be made of any suitable material, such as cast-iron; but the most 5 suitable I find to be wrought-iron tubing, joined by couplings, elbows, &c., like gas-piping. This is the kind of frame-work shown in the drawings, and I find it economical, light, and very strong, and easily put together. 10 It is of course applicable to other kinds of machines besides those described in this specification.

I claim—

- 15 1. In an apparatus for drying or recovering spent hops, the horizontal cylinders A B, arranged in the same plane, having shafts provided with arms set in opposite directions, in combination with means for receiving the material from the drying-chamber and elevating 20 the same, whereby it is discharged into the separating-cylinder, substantially as described.
2. The cylinder A, heated as described, and having central revolving shaft, A', carrying beaters A², in combination with rod G and 25 the disk carried by the revolving shaft G³, substantially for the purpose set forth.
3. In combination with cylinder A and

spout D, the hopper provided with the upper and lower shafts and grating, as described, and having the sliding panel D' and spring 30 D², said lower shaft having the arm for operating the panel, substantially as set forth.

4. In combination with the drying-cylinder and spout D, the hopper provided with the shafts and grating, as described, and having 35 the sliding panel D', spring D², and adjustable door D³, substantially as set forth.

5. In combination with cylinder A, the hopper C, provided with shafts C' and C², and wings or knives C³, and grating P, substantially 40 as and for the purpose set forth and shown.

6. In an apparatus for treating spent hops, the combination, with the drying-cylinder A, of an exhaust-fan for removing the fumes, 45 substantially as described.

In witness whereof I, the said EDWARD DAVIES, have hereunto set my hand in the presence of two subscribing witnesses.

EDWARD DAVIES.

Witnesses:

ALFRED J. BOULT,
BERNHARD DUKES.
